ROTARY PUMP

Cromwell Hanford Varley, Acton, London,
England, assignor to Varley Pumps and En-
gineering Limited, London, England

Application November 8, 1933, Serial No. 697,207
In Great Britain July 27, 1932

7 Claims. (Cl. 103—131)

This invention relates to pumps of the class wherein the fluid to be operated upon is admitted into a conduit extending between an inlet and an outlet and therein subjected to displacement, in volumes which are comparatively suddenly released to the discharge, by relatively moving members having co-operating parts, for instance, intermittently forming contacts or sealing regions, which determine the various events of the cycle 5 irrespective of pressure. It is concerned thus with pumps of a class embracing those set forth for instance in my United States patent specification No. 1,560,624 and British patent specifications Nos. 154,261 and 217,615 and has for its 10 object improvements with a view to the more satisfactory and efficient, e. g. smoother and quieter working of pumps of such class.

It has been found that in the operation of the aforesaid class of pump with substantially incompressible fluids as distinct from air or other gaseous or elastic fluids, a knocking occurs, more especially when the pump is worked at high speeds and high rates of delivery; and investigation into this has shown that the knocking is due 25 to differences between the fluid pressure at the discharge end of the conduit and the pressure of the said displaced volumes at the instants when they are released to the discharge; the latter pressure being less than the former, with a more or less violent counter-flow action as a result. For instance, in the patented construction of pumps referred to above the trouble arises due to the crescent or like chamber (there may be more than one) enclosed between the moving contacts of the 30 displacer and the casing not being fully filled with liquid at the point of the cycle when it is opened to the discharge side of the pump and by an inward rush of liquid into the rarefied liquid in said chamber from the discharge side in a direction counter to the direction of paracyclic movement of the displacer; such movement being "paracyclic" as defined in the earlier patent specifications above referred to.

According to this invention fluid is introduced 45 into a volume of fluid being operated upon prior to release of the latter to the discharge. Thus, in a pump of the class referred to means are provided for introducing fluid into a volume of fluid entrained in the operating conduit (or in process 50 of being entrained e. g. before it is quite isolated from the suction) at a point in the cycle sufficiently in advance of the instant at which the entrained volume is released to discharge pressure to ensure that at such instant the said 55 volume will be completely filled with fluid. Con-

veniently such means comprises a chamber of a capacity variable against resilient resistance and adapted so to be placed in communication with and isolated from a volume of fluid being operated upon as to receive fluid from the operating 60 conduit at the pressure of the pump discharge and to re-introduce such fluid at the said point of the cycle.

Other features of the invention and its preferred mode of application to pumps operating 65 in accordance with the aforementioned prior patents will be set forth in the description and claims which follow:—

Referring to the accompanying drawings:—

Figures 1 and 2 are diagrammatic sections of a 70 known construction of pump, the displacer element occupying top dead-centre and bottom dead-centre positions respectively;

Figure 3 is an inside elevation of a cover for 75 a pump of the kind shown in Figures 1 and 2 having superimposed thereon in correct relationship a displacer and its co-operating casing interior;

Figure 4 is an outside elevation of the cover shown in Figure 3;

Figure 5 is a section on the line X—X of Figure 80 4; and

Figure 6 is a section on the line Y—Y of Figure 4.

In the construction of pump shown in Figures 1 and 2 of the drawings, the displacer *a* executes 85 a paracyclic motion, as indicated by the arrows *x*, *x* and by the circle *y* which is traced by a point *z* centrally of the displacer, within the C-shaped interior of a stator or casing *b*; the fluid being entrained in the outer crescent-like 90 chamber *c* (see Figure 1) and, as the displacer moves in a cycle through the position shown in Figure 2, being displaced from the pump inlet at *i* to the discharge or outlet at *d*. A similar operation takes place in the inner crescent chamber *c* (see Figure 2) and efficient sealing between 95 the displacer and the stator is provided by co-operation of the resilient contact pieces *e*₁, *e*₂, *e*₃, *e*₄, *e*₅, *e*₆ with complementary arcuate surfaces *f*₁, *f*₂, *f*₃, *f*₄, *f*₅, *f*₆; all as already well known. 100 Considering the action of the above device upon water or other fluid in the outer crescent *c* it will be seen that in Figure 1 the seal between *e*₁ and *f*₁ is about to be broken and the fluid in the outer crescent *c* about to be thus released to the discharge side; while a seal has just been effected 105 between *e*₂ and *f*₂ behind the volume of fluid in the said crescent.

Referring now to Figure 3, and introducing one 110 convenient mode of applying the invention to

such a construction of pump, the displacer *a* when in the full line position, a few degrees before top dead-centre and before the contacts *e*₁, *f*₁ separate, will be seen to have just uncovered the 5 radially outermost side of the port *p* formed in the side cover *g* of the pump; when it is in the chain-dotted position *a*₁, at an earlier stage of the cycle it completely covers the said part, and at a still earlier stage just before contact is first 10 established between the said contacts, it has just closed or covered said port at the same side thereof. The outer edge of the port is of complementary shape to the outer edge of the displacer, so as to ensure sharp uncovering or opening of the 15 port.

It will be understood also that so far as the outer crescent *c* is concerned the port will thus be opened from some few degrees before top 20 centre position while the displacer performs the greater part of the cycle which restores it to the position just before contact at *e*₁, *f*₁ is re-established.

The side cover, as shown in Figures 4, 5 and 6, has cast integrally on its exterior opposite the 25 port *p* a housing *h* comprising a portion having a cylindrical bore *j* into which the port *p* opens. Freely slideable within the bore *j* is provided a hollow cylindrical piston *k*, called the compensator piston, which is resiliently loaded by a 30 helical compression spring *l* of suitable strength, the outer end of which spring is conveniently restrained by the cover *h*, suitably applied to the housing. An annular enlargement *j*₁ of the housing interior at the inside end of the bore *j* facilitates manufacture, more particularly machining 35 of the bore *j*. The outer side of the piston is in communication with the pump suction via the passages *m*, *m*₁, *m*₂, *m*₃ and opening *m*₄ which form part of a suitable by-pass valve device, 40 preferably one so constructed and operating that on a predetermined fluid pressure being reached the fluid escapes past co-operating valve faces and acts upon an increased area of the valve proper. Preferably such valve comprises means 45 for ensuring a leak-away of fluid inhibitive to premature opening of the valve proper at low pressures and to such end may have a seating region of smaller area than the valve proper and connected with a restricted annular space surrounding the latter, or may have means permitting partial escape of fluid through the valve proper, such as holes in the latter opposite an 50 annular space in the vicinity of the valve seat. The form of valve shown in the drawings Figs. 5 and 6 comprises co-operating surfaces of the 55 valve proper and seating thereof, the latter having a skirt or its equivalent embracing the end region of the former and defining a narrow annular clearance divergent or stepped to a larger diameter in the direction of lift of the valve proper. The latter is of cylindrical form, having spring or like loading means therefor, and fluid passage 60 means placing the back of the valve proper in communication with a chamber which surrounds the co-operating seating parts and contains said 65 annular space, and as shown there may also be incorporated dashpot or like damping means operative upon the valve proper. In operation 70 of the compensator above described, the piston will occupy an intermediate position in the bore *j* dependent upon the pressures acting upon it.

Describing now the operation of the pump with reference to the port *p* and compensator device and their action in respect of the outer crescent 75 chamber *c*; while the displacer *a* moves through

the upper part of its cycle and the elements *e*₁, *f*₁ are disengaged the fluid in said chamber *c* is open to the discharge, and the port *p* being uncovered, a pressure of fluid equal to the discharge pressure acts upon the end of the piston *k* forcing the same back against the spring *l* to an extent depending upon the strength of the latter and the head against which the pump is operating. When the displacer reaches the complete cut-off position with respect to the port *p*, just prior to its reaching the chain-dotted position in Figure 3, the fluid under said pressure acting upon the piston in the space *j* is isolated from both crescents *c* and *c*₁ and it remains so until just before the displacer reaches the full-line position, uncovering the port to the outer crescent *c*. Pressure reduction or rarefaction of the fluid in the said crescent *c*, occurring in the ordinary way with such a pump from the said full-line position of the displacer until the latter reaches the position in which it is shown in Figure 1, is prevented or compensated by the timely and controlled opening of the port *p* with admission therethrough into the crescent *c* of fluid substantially at the discharge pressure from the piston *k*. By this means pressure difference on opposite sides of the sealing elements *e*₁, *f*₁ as these are severed is eliminated and backward rush of fluid from the region of the discharge or outlet *d* in counterflow to the movement of the displacer no longer takes place. During continuation of the cycle fluid is again charged into the chamber of the compensator piston as above; it is then isolated at discharge pressure and released again into the crescent *c*, these events 110 taking place with each complete cycle of the displacer.

The same series of events occurs during every cycle with respect to the inner crescent *c*₁, the port *p* having its radially innermost edge suitably positioned and shaped to conform with the inner edge of the displacer for co-operation of these parts in an appropriate manner.

It will be understood that for correct operation of a compensator device such as that described above the shape and disposition of the port *p* is of primary importance in order that the introduction of fluid therethrough may be suitably controlled, and will be related not only to the shape of the displacer but also to the 123 area of the piston *k*, to the resistance of the spring *l* and to the working pressure differences between discharge and suction sides of the pump. It has been found by experiments in connection with a pump as shown, and operating against 127 about fifteen pounds pressure per square inch in which the port *p* was arranged to be opened to the outer crescent *c* with the displacer *a* at positions ranging from top dead-centre (as in Figure 1) to 35° before top dead-centre, that 131 some 15° to 20° gave satisfactory results. In Figures 3, 4 and 5 a port has been shown so arranged as to have opened sharply some few degrees before 22½° in advance of top dead-centre. In practice it is best arranged to open at the 135 22½° position to allow for tolerance in casting where the port is not to be machined. Premature uncovering of the port produces excessive displacement of the compensator piston owing to the port opening substantially before the contacting elements *e*₂, *f*₂ come into operation, and the fluid at the pressure of the compensator being discharged or short circuited back to the suction. Also, as will be obvious, in such a case a reduction of pumping capacity is experienced, 145 150

- and further the substantial movement of the piston, necessarily accompanied by considerable flow of fluid back into the compensator each cycle produces pulsation of the pump discharge.
- 5 Whereas a pump unprovided with a compensator device operating as above described may require means for elimination or reduction of pulsations as for instance air chambers or vessels connected with suction and discharge sides, or
- 10 alternatively a "balance valve" comprising spring loaded piston connected at opposite sides directly with the discharge and suction sides, the compensator device when fitted (and subject to the foregoing considerations) serves also in this
- 15 capacity, notwithstanding that the piston thereof corresponding to the piston in the "balance valve" is isolated from the pressure of the discharge side for some 30° while the port p is completely covered by the displacer.
- 20 By operating according to the invention the action of a pump can be considerably smoothed and whereas considerable "hammer" or knocking took place in one construction of pump delivering about fifteen gallons per minute, the fitting of a compensator not only eliminated such defect but enabled the pump to be speeded up to twenty gallons per minute without recurrence of the trouble.
- It is to be understood that modifications and additions may be introduced within the scope of the invention as herein defined, the specific description having been given by way of example only.
- I claim:
- 35 1. In a pump having a casing defining a pumping chamber extending between inlet means and outlet means and a displacer cyclically movable therein and co-operating therewith across the pumping chamber when in movement to perform at determinate positions of the displacer the events of entraining fluid from the inlet region of the pumping chamber, displacing it towards and releasing it to the outlet region, a fluid chamber of a capacity governed by a resiliently movable partition and adapted to receive fluid at discharge pressure, and means for introducing such fluid at said pressure into said pumping chamber at a point of the pumping cycle closely in advance of the release event.
- 50 2. In a pump having a casing defining a pumping chamber extending between an inlet and an outlet, a displacer cyclically movable therein and fluid sealing devices co-operating in succession across the pumping chamber with said casing and said displacer when the latter is in movement to determine the events of entraining fluid from the inlet of the pumping chamber, displacing it towards and releasing it to the outlet, a fluid chamber of a capacity governed by a resiliently movable partition and adapted to receive fluid at discharge pressure, port means connecting said chamber with said pumping chamber and adapted to be covered by said displacer during a portion of the pumping cycle between an entraining event and a successive release event, and to be uncovered by said displacer closely in advance of such release event.
3. In a pump having a casing defining a pumping chamber extending between an inlet and an outlet and a displacer cyclically movable therein and co-operating therewith across the pumping chamber in movement to determine the events of entraining fluid from the inlet displacing it towards and releasing it to the outlet, a fluid chamber adapted to receive fluid at discharge pressure of a capacity governed by resilient means yieldable against such pressure, port means connecting said chamber with said pumping chamber at a region thereof disposed nearer to the outlet than to the inlet and adapted to be covered and uncovered by said displacer during a portion of the pumping cycle between associated entraining and release events, said port means having an edge conforming in shape to a marginal region of said displacer and located to coincide with such region when the displacer occupies a position slightly in advance of the release event. 80
4. In a pumping combination according to claim 1, passage means separated from said variable capacity fluid chamber by said resiliently movable partition and leading to the inlet region of said pumping chamber. 90
5. In a pumping combination according to claim 1, passage means separated from said fluid chamber by said resiliently movable partition and leading to the inlet side of the pump, passage means leading from the discharge side of the pump to the inlet side of the pump and relief valve means operative in said second-mentioned passage means. 100
6. In a pumping combination according to claim 1, passage means separated from said fluid chamber by said resiliently movable partition and leading to the pump inlet side of the pump, passage means leading from the discharge side of the pump to the inlet side of the pump, including a resiliently loaded valve co-operating with a port leading from said second passage means to the discharge side of the pump and having a body portion in part occupying said first passage means leading from said resiliently movable partition. 115
7. For pumps operating upon substantially incompressible fluids and comprising a casing defining a pumping chamber within which a displacer executes a cyclic movement to displace fluid from an inlet at one end to an outlet at the other, a side cover for said casing comprising an external housing containing a compensator chamber and passage means connecting the same to the inlet side of the pump and to the outlet side of the pump, a port penetrating said cover from said compensator chamber to the pumping chamber in a position such as to be in the path of said displacer, a partition reciprocatable in a fluid-tight manner in said compensator chamber between said port and said passage means, means constraining said partition with resilient force towards said port, and relief valve means in said housing and operative between said inlet side and said outlet side. 125
